UNITED STATES PATENT OFFICE.

MARTIN KATZ, OF BROOKLYN, NEW YORK.

MOUNTING OF STORE WINDOWS.

Application filed March 17, 1924. Serial No. 699,876.

To all whom it may concern:

Be it known that I, MARTIN KATZ, a citizen of the United States, and resident of Brooklyn, in the county of Kings and State of New York, have invented certain new and useful Improvements in Mountings of Store Windows, of which the following is a specification.

This invention relates generally to the mounting of store windows, having particular reference to the means for securing the glass panes to the frame.

In connection with store windows it is desirable to provide ventilating passages spaced along one or more of the edges of the glass, the passages at the bottom edge of the glass also serving to conduct to the outside of the window such moisture as may condense on the inner face of the glass and run down the same, or may run down the glass while the latter is being washed.

The present invention has for an object to provide a simple means for mounting the glass in the frame which includes metal sheathed retaining or moulding strips fastened to the window frame and engaging the glass and having the ventilating and water conducting passages formed in a novel manner therein.

For further comprehension of the invention, and of the objects and advantages thereof, reference is had to the following description and accompanying drawing, and to the appended claims in which the various novel features of the invention are more particularly set forth.

Figure 1 of the drawing is a fragmentary outside face view of a window showing the glass engaged by my improved means with the sill of the window.

Figure 2 is a horizontal sectional view taken on the line 2—2 of Fig. 1.

Figure 3 is a transverse vertical sectional view taken on the line 3—3 of Fig. 2.

Figure 4 is a similar view taken on the line 4—4 of Fig. 2.

Figures 5 and 6 are fragmentary longitudinal sectional views of the retaining strips, showing the latter with the sheathing in place but not pressed into the passage-forming recesses in the wooden fillers, these views being taken on the planes indicated by the lines 5—5 and 6—6 respectively on Fig. 4.

In the drawing, the reference numeral 10 indicates the sill of a window, this sill be-

ing of ordinary construction and may be covered on front and top by a metal facing strip 11. The glass pane is shown at 12 and it rests at its lower edge on a number of spacer blocks 13 mounted on the sill 10, the bottom of the glass being thus spaced above the top of the sill. The spaces between these blocks 13 provide passages leading transversely under the glass between the inner and outer sides thereof.

The glass is engaged on its outer and inner sides by outer and inner moulding or retaining strips, indicated generally at 15 and 16 respectively, which are fixed upon the top of the sill 10, these strips each comprising an inner wooden filler, and a sheathing of sheet metal such as copper. The wooden filler of the outer strip is indicated at 15' and the metal sheathing at 15^a, while the corresponding parts of the inner strips are numbered 16' and 16^a respectively. These strips are preferably formed to engage the glass 12 along the top edges only of their adjacent sides, the said strips being recessed along adjacent sides as shown to provide overhanging top portions 15^b and 16^b which engage the glass.

These strips are formed in a novel manner to present ventilating and water conducting passages which communicate with the above mentioned spaces between the blocks 13, the passages in the strip 16 extending through the overhanging top portion thereof, while the passages through the strip 15 are located at the underside thereof, the respective passages being formed by recesses in the said strip. In order to provide the said recesses, while leaving the metal sheathing continuous and unbroken, the wooden filler members 15' and 16' are formed with suitable recesses such as shown at 21 and 22 in Figs. 5 and 6, the recess 21 extending transversely of the strip 15' at the bottom thereof, and the recess 22 ex-

100
105
110

extending downwardly through the overhanging top part of 16^b of the strip 16'. The metal sheathings are then die-drawn over the filler strips in well known manner and are hammered or otherwise pressed inwardly at the points where the said recesses 21 and 22 occur. When the strips 15 and 16 are in place engaging the glass 12, horizontal passages 24 are formed between the strip 15 and the sill 10, and vertical passages 25

105
110

are formed between the inner strip 16 and the glass 12. The strips on opposite sides

of the glass may be secured independently of each other by screws or other suitable means in such manner as to permit the insertion or removal of the glass from either 5 side of the window frame.

The outer strip 15 may be suitably formed at its top and outer side to shed the rain, while the top of the inner strip 16 is preferably concaved or channel shaped in cross 10 section, as shown, to prevent water from discharging over the rear or inward side thereof. As shown in Fig. 4 of the drawing the water and air passages 25 are formed by bending portions of the channeled shaped 15 sheathing downwardly and inwardly into the recesses indicated at 22.

While I have shown the outer and the inner retaining strips applied to a sill member only, it is to be understood that similar 20 strips may extend around and support all side edges of the glass and provide therefor corresponding ventilating passages by means of which the air on opposite sides of the glass may in a measure become neutralized as regards pressure and temperature and thus tend to avoid breakage of the glass or the formation of frost thereon.

In construction the sheathing is composed of relatively thin metal and is closely drawn 30 over and against the filler members, enclosing the latter on all side faces in an unbroken manner, and protecting the same against contact with water and air, and the consequent decay therefrom.

While I have shown and described the 35 filler members as being formed with recesses prior to the application of the metal sheathing, it is to be understood that this method is adapted more particularly in situations 40 requiring relatively hard filler members of extended length, and with deep recesses. And in other situations in which relatively soft wood may be used as a filler member, the metal sheathing may be directly drawn 45 thereover and the necessary recesses formed by compressing the sheathing into the soft filler member.

Having thus described my invention what 50 I claim as new and desire to protect by Letters Patent of the United States is as follows:

1. In a window, a sill, a glass pane supported thereby, said pane being arranged to leave passages extending transversely 55 thereunder, inner and outer retaining strips on said sill engaging opposite faces of said pane, the inner retaining strips being formed with a number of vertical recesses on the side thereof adjacent the pane, and the outer strips being formed with a number of transversely extending recesses on its under side.

2. In a window, a sill, a glass pane supported thereby, said pane being arranged to leave passages extending transversely thereunder, a retaining strip mounted on the 60

sill and engaging the said pane, said strip being recessed at points along the side thereof of which engages the pane to provide vertical passages communicating with the said transverse passages and said strips comprising a wooden filler and a metal sheathing, the metal sheathing extending continuous and unbroken along the said recesses. 70

3. In a window, a sill, a glass pane supported thereby, said pane being arranged to leave passages extending transversely thereunder, a retaining strip mounted on the sill and engaging the said pane, said strip being recessed at points along the side thereof of which engages the pane to provide vertical passages communicating with the said transverse passages. 75

4. In a window, a sill, a glass pane supported thereby, said pane being arranged to leave passages extending transversely thereunder, a retaining strip mounted on the sill and engaging the said pane, said strip being recessed at points along the side thereof of which engages the pane to provide vertical passages, said strips comprising a wooden filler and a metal sheathing, the metal sheathing extending continuous and unbroken along the strip. 80

5. In a window, a sill, a glass pane supported thereby, said pane being arranged to leave passages extending transversely thereunder, a retaining strip mounted on the sill and engaging the said pane, said strip having a longitudinal channel formed in the top thereof, and being recessed at points along the side thereof which engages the pane to provide vertical passages, said passages communicating at one side with the bottom of said channel. 90

6. In a window, a sill, a glass pane supported thereby, said pane being arranged to leave passages extending transversely thereunder, a retaining strip mounted on the sill and engaging the said pane, said strip having a longitudinal channel formed in the top thereof, and being recessed at points along the side thereof which engages the pane to provide vertical passages, said passages communicating at one side with the bottom of said channel, said strips comprising a wooden filler formed with recesses along one side and a metal sheathing extending unbroken along the filler strips and pressed into the said recesses. 100

7. In a window, a sill, a glass pane supported thereby, and a retaining strip engaging said pane and comprising a filler member formed with a number of recesses along one side thereof, and a metal sheathing extending unbroken along the filler member and pressed into said recesses. 110

8. In a window setting, a retaining strip comprising a filler member formed with a transverse recess along a side thereof, and a metal sheathing extending unbroken over the 115

filler member and pressed into said recess and against the walls thereof.

9. In a window setting, a retaining strip comprising a wooden filler member formed with transverse recesses along a side thereof, and a metal sheathing extending over the filler member and pressed into said recesses and against the walls thereof.

10. In a window setting, a retaining strip comprising a filler member having a metal

sheathing extending unbroken and enclosing said member on all side faces thereof, the said sheathing being pressed into said filler member and forming transverse recesses extending along a side of the strip. ¹⁵

Signed at New York, in the county of New York and State of New York, this 15th day of March, A. D. 1924.

MARTIN KATZ.
